Radio Corporation of America, a corporation
of Delaware

Application March 31, 1934, Serial No. 718,354

14 Claims. (Cl. 178—7.1)

My invention relates to electrical signalling apparatus and particularly to direct-current amplifiers.

In many electrical circuits it has been found desirable to utilize direct-current amplifiers rather than amplifiers which can not transmit a direct-current component. Direct-current amplifiers, however, have a serious defect in that they have a tendency to "drift". That is, with 10 no signal on the amplifier, the output current will gradually increase or gradually decrease over a period of several minutes.

In high gain direct-current amplifiers, such as are especially desirable for use in television transmitters, the "drift" is so serious that heretofore it has been practically impossible to use direct-current amplifiers in television transmitters. Their use in such transmitters is desirable in order that the direct-current component of 20 the picture background may be transmitted.

It is an object of my invention to provide an improved direct-current amplifier and an improved method of operating the same.

More specifically, it is an object of my invention to provide a direct-current amplifier which is stable in operation and which does not "drift".

It is a further object of my invention to provide an improved television or facsimile system.

It is a still further object of my invention to 30 provide an improved television or facsimile transmitter which includes a high gain direct-current amplifier.

In practicing my invention, I provide a direct-current amplifier with a closed loop circuit so 35 connected that energy may be fed from the output circuit of the amplifier to its input circuit in the proper phase to oppose any change in voltage or current at the output circuit. The signals to be amplified, such as picture signals, 40 are impressed upon the amplifier input circuit periodically whereby there are intervals during which no signal is impressed thereon.

The loop circuit is so designed that it is ineffective during the period a signal is impressed 45 upon the amplifier, the signal being given a positive polarity to accomplish this. During the interval of no signal, an impulse of negative polarity, such as a synchronizing impulse, is impressed upon the amplifier. This negative 50 impulse causes a flow of current through the loop circuit to charge a condenser and control a bias voltage in the amplifier during the succeeding signal period, this flow of current having a magnitude which depends upon any "drift" that has 55 occurred during the preceding signal period. In

this way the degenerative loop circuit prevents any appreciable "drifting" of the amplifier even though it has a very high gain.

Other objects, features and advantages of my invention will appear from the following description taken in connection with the accompanying drawings, in which:

Figure 1 is a block diagram of a television system embodying my invention;

Fig. 2 is a fragmentary view of the scanning disc shown in Figure 1;

Fig. 3 is a curve showing the character of the signals impressed upon the main direct-current amplifier of the transmitter;

Fig. 4 is a circuit diagram of the apparatus shown in Figure 1;

Fig. 5 is a set of curves showing the operation of my improved direct-current amplifier;

Fig. 6 is a block diagram showing a modification of the transmitter circuit illustrated in Figure 1;

Fig. 7 is a curve which is referred to in explaining a modified form of my invention;

Figs. 8 and 9 are plan and side views, respectively, of apparatus which may be employed in obtaining the operation indicated by the curve of Fig. 7; and

Fig. 10 is a view of a portion of a scanning disc and its mask which may be employed in the system shown in Figs. 8 and 9.

Referring to Figure 1, a television transmitter is shown at the left-hand side of the drawing while a television receiver is shown at the right-hand side of the drawing, the transmitter and receiver being connected by a transmission channel as indicated by the dotted lines 1 and 3. The channel has been exemplified as conductive merely for purpose of convenience, it being of course understood that my invention is applicable to the amplifiers utilized in a radio transmitter or radio receiver. In the particular embodiment illustrated, the transmitter is shown set up for the transmission of the pictures on a motion picture film indicated at 5.

The film 5 is scanned by means of a scanning disc 7 driven by a motor 9, the scanning disc preferably being of the type described and claimed in my co-pending application Serial No. 544,959, filed June 17, 1931, and assigned to the same assignee as this application. As indicated in Fig. 2, a disc of this type has a row of scanning holes 11, and a row of synchronizing holes 13 arranged on a circle near the circumference of the disc.

Light for scanning the picture is supplied from 55

- a suitable source 15 and passed through an optical system indicated at 17, the light passing through the scanning holes 11 of the disc and through the film 5 onto a photoelectric cell 19. 5
5 The photoelectric cell 19 is connected through a battery 21 to the input circuit of a direct-current amplifier 23.

The output circuit of the amplifier 23 is connected by means of a coupling resistor 25 and 10 inductance coil 27 to the input circuit of the main direct-current amplifier 29 which has a high gain. The coil 27 is employed for improving the high frequency response of the system. The coupling circuit between the amplifiers 23 and 29 also 15 includes a condenser 31, which is utilized, as explained hereinafter, in combination with a balancing circuit for preventing "drifting" of the direct-current amplifier 29.

The output circuit of the amplifier may be connected to the transmission line 1-3, as indicated 20 on the drawings, or it may be connected to a radio transmitter for transmitting the picture signal over a radio channel in accordance with well known practice.

25 In order to prevent drifting of the high gain amplifier 29, a balancing network indicated at 33 is provided, its input circuit being connected to the output circuit of the amplifier 29 and its output circuit, exemplified by the variable resistor 30 shown in dotted lines, being connected across the condenser 31.

A suitable light source 35 and optical system 37 are provided for passing light through the synchronizing openings 13 in the disc 7 and upon a 35 photo-electric cell 39. The photo-electric cell 39 is connected through a battery 41 to the input circuit of a synchronizing amplifier 43. The output circuit of the synchronizing amplifier 43 is connected to the input circuit of the direct-current amplifier 23 through a conductor 45 and a connection which includes a condenser 47 and a resistor 49.

As explained in my above mentioned co-pending application, the synchronizing amplifier 43 is 45 so designed that it supplies synchronizing pulses to the direct-current amplifier 23 which have a polarity opposite to the polarity of the picture signals, the scanning disc being provided with masks so positioned that the synchronizing impulses occur during the intervals that no picture 50 signals are being transmitted.

The character of the signal applied to the input circuit of the amplifier 23 is shown in Fig. 3. It will be seen that each scanning line of the picture 55 is represented by positive voltage signal waves 51, these signal waves being separated by short intervals. During these intervals synchronizing impulses 53 which have a negative polarity are impressed upon the amplifier 23. In accordance 60 with my invention, these negative impulses are utilized both for synchronizing the television apparatus and for controlling the balancing circuit 33 whereby the high gain direct-current amplifier 29 is stabilized, or they may be utilized 65 solely for stabilizing the amplifier.

The receiving apparatus shown in Fig. 1 comprises a direct-current amplifier 55 which amplifies the picture signal and impresses it upon the control grid 57 and cathode 59 of a cathode ray 70 receiving tube 61. The cathode ray tube is provided with deflecting coils 63 and 65 connected to oscillators indicated at 67 and 68, respectively, which provide saw-tooth waves for deflecting the cathode ray beam both in a horizontal and in a 75 vertical direction. The deflecting oscillators 67

and 68 are maintained in synchronism with the transmitting apparatus by means of a synchronizing selector 70 connected to the transmission line 1-3 for supplying synchronizing pulses to the deflecting oscillators. A separating circuit 66 5 is included in the circuit between the selector 69 and the oscillators 67 and 68 for the purpose of separating the horizontal and vertical synchronizing impulses. This method of maintaining 10 synchronism between the transmitting and receiving apparatus is described and claimed in my above-mentioned co-pending application and in application Serial No. 565,983, filed September 30, 1931, in the name of R. D. Kell, and assigned to 15 the same assignee as this application.

The invention will be more clearly understood by referring to the circuit diagram in Fig. 4 in which parts similar to those in Fig. 1 are indicated by like reference numerals. The direct-current amplifier 23 comprises an electric discharge tube 71 having a cathode 73, a control grid 75, a screen grid 77, and an anode 79. The control grid 75 is maintained at the proper negative bias with respect to the cathode 73 by means of a biasing battery 81 and a resistor 83. The 20 photo-electric cell 19 comprises a cathode 85 and an anode 87, the cathode 85 being connected to the control grid 75 and the anode 87 being connected through the battery 21 to the cathode 73. 25

The anode 79 of the tube 71 is maintained at 30 the proper positive potential by means of a connection through the plate resistor 25 and coil 27 to the positive terminal of a plate battery 89. The screen grid 77 is connected to a suitable point on battery 89. 35

The main direct-current amplifier 29, which has a gain so high that precautions must be taken to avoid "drifting", comprises an electric discharge tube 91 having a cathode 93, a control grid 95, a screen grid 97, and an anode 99, and 40 a second electric discharge tube 101, preferably of the pentode type, having a cathode 103, a control grid 105, a suppressor grid 107, a screen grid 109, and an anode 111. 45

The control grid 95 of the tube 91 is connected directly to the anode 79 of the preceding tube 71. The cathode 93 is connected to the lower terminal of the coil 27 through the condenser 31 and through the balancing circuit 33 in a manner described hereinafter. 50

The anode 99 is maintained at a positive potential by a connection through a plate resistor 113 and a coil 115 to the positive terminal of a plate battery 117, the screen grid 97 being connected to a suitable positive point thereon. 55

The control grid 105 of the pentode 101 is connected directly to the anode 99 of the tube 91. The cathode 103 is connected to a suitable point on the plate battery 117 for biasing the control grid 105 to a proper value. The anode 111 of the pentode 101 is connected through a plate resistor 119 to the positive terminal of a plate battery 121, while the suppressor grid 107 and the screen grid 109 are connected to suitable 60 points thereon. 65

The balancing circuit comprises an electric discharge tube 123 having a cathode 125, a control grid 127, a screen grid 129, and an anode 131. The control grid 127 is connected through a biasing battery 133 to the anode of the direct-current amplifier 29. The cathode 125 is connected through a conductor 135 to the cathode 93 of the amplifier tube 91, whereby the connection of input circuit of the balancer tube 123 75

to the output circuit of the direct-current amplifier 29 is completed.

The anode 131 is connected through a plate resistor 137 to the positive terminal of a plate battery 139, while the screen grid 129 is connected to a suitable point thereon.

The output circuit of the balancer tube 123 is connected across the condenser 31, this connection being through the conductor 135 and through a biasing battery 141 which has its positive terminal connected to the anode 131 and its negative terminal connected through a conductor 143 to the grid side of the condenser 31.

The biasing battery 133 is preferably given a value such that the balancer tube 123 is biased slightly beyond the cut-off point. Because of this, the picture signals, which have a negative polarity at the point where they are impressed upon the balancer tube, have no effect thereon, while the synchronizing impulses, which have a positive polarity at this point in the circuit, produce a pulse of current in the output circuit of the balancer tube for charging the condenser 31.

The effect of these current pulses in the output circuit will be better understood by tracing the biasing circuit for the tube 91 of the amplifier 29. This circuit may be traced from the cathode 93 through the conductor 135, the plate battery 139, the plate resistor 137, the biasing battery 141, the conductor 143, and through the coil 27 and plate resistor 25 to the control grid 95. It will be noted that the voltage between the cathode 125 and the plate 131 has a polarity opposed to that of the biasing battery 141. Therefore, if the positive voltage on the plate 131 decreases, the negative bias applied to the control grid 95 is increased. It follows, therefore, that the appearance of a pulse of current in the plate circuit of the balancer tube 123 tends to increase the bias on the control grid 95, since such a pulse of current lowers the voltage on the anode 131 due to the IR drop in the resistor.

Because of the condenser 31, however, the change in bias on the control grid 95 varies gradually with changes in the magnitude of the plate current pulses, these pulses charging up the condenser 31 to a value depending upon their magnitude. The condenser 31 and the plate resistor 137, which is effectively in shunt to the condenser, have sufficiently large values to integrate the plate current pulses whereby a bias is applied to the input circuit of the high gain amplifier 29 which varies gradually in accordance with any "drifting" of the amplifier.

The synchronizing amplifier 43, which supplies the synchronizing or control pulses during the intervals of no picture signals, comprises an electric discharge tube 145 having a cathode 147, a control grid 149, a screen grid 151, and an anode 153. The control grid 149 is maintained at a suitable bias by means of a connection to the cathode 147 through a resistor 155 and a biasing battery 157. The cathode 159 of the photoelectric cell 39 is connected directly to the control grid 149 while the anode 161 is connected through the battery 41 to the lower terminal of the resistor 155.

The anode 153 is connected through a plate resistor 163 to the positive terminal of a plate battery 165, while the screen grid 151 is connected to a suitable point thereon. The output circuit of the synchronizing amplifier 43 is connected to the input circuit of the first direct-current amplifier 23 by means of the conductors 45 and 135 and condenser 31 and by means of the con-

nection from the anode 153 to the control grid 75 of the amplifier tube 71 through the condenser 47 and resistor 49.

It will be evident that light striking the photoelectric cell 39 of the synchronizing circuit and the light striking the photoelectric cell 19 of the picture amplifier cause pulses of current at the input of the main direct-current amplifier 29 which are of opposite polarity, since the synchronizing light pulse is amplified through two amplifiers and the picture impulse is amplified through only one amplifier.

At the receiving system, the direct current amplifier 55 comprises an electric discharge tube 167 having a cathode 169, a control grid 171, a screen grid 173, a suppressor grid 175, and an anode 177. The control grid 171 is connected through the transmission line conductor 1 to the output circuit of the direct-current amplifier 29 of the transmitter. The cathode 169, which is heated through a transformer winding 179, is connected through the other transmission line conductor 3 to the proper point on the plate battery 121 for maintaining the control grid 171 at a suitable bias potential.

The anode 177 is connected through a plate resistor 181 to the positive terminal of a plate battery 183 while the screen grid 173 is connected to a suitable positive point thereon. The control grid 57 of the cathode ray tube 61 is connected through a variable tap to a point on the plate resistor 181, while the cathode 59 is connected to a suitable point on the plate battery 183 for biasing the control grid 57 to the proper value.

The synchronizing selector 70 comprises an electric discharge tube 69 having a cathode 185, a control grid 187, a screen grid 189, and an anode 191. The control grid 187 and cathode 185 are connected to the transmission line conductors 1 and 3 respectively, the cathode connection including a biasing battery 193 having the proper value for biasing the tube 69 beyond the cut-off point.

The anode 191 is connected through a plate resistor 195 to the positive terminal of a plate battery 197, while the screen grid 189 is connected to a suitable point thereon. The output circuit of the selector tube 69 is connected to the separating circuit 66 by means of a connection through a coupling condenser 199 and by means of a connection through ground indicated at 201.

It will be seen that since the synchronizing selector tube 69 is biased beyond the cut-off point, it will not be affected by picture signals, while the synchronizing impulses, which have a positive polarity at this point in the circuit, will be impressed upon the deflecting oscillators 67 and 68.

Referring again to the operation of the high gain direct-current amplifier 29 and its associated balancing circuit 33, the action of the balancer tube 123 and the biasing condenser 31 is shown by the curve in Figure 5. In this figure the curve 203 represents the plate current of the balancer tube 123 plotted against voltage applied to its control grid. The curves for the picture and synchronizing signals 51 and 53, respectively, are drawn along a time axis which passes through the value of grid voltage on the abscissa which is equal to the bias voltage on the balancer tube 123. It will be noted that this bias voltage is greater than the value required for complete cut-off of the tube. The curves drawn 75

in solid lines represent a condition of the amplifier 29 where there is no tendency to drift.

Since the balancer tube 123 is biased beyond the cut-off point, the picture signals have no effect upon the balancer circuit. The synchronizing impulses, however, have the proper polarity and magnitude to cause plate current to flow in the balancer tube each time a synchronizing pulse occurs. These pulses of plate current are represented by the solid line rectangles 205. They are integrated by means of the condenser 31 to a substantially constant current having a value indicated by the dotted line 207. Thus it will be seen that the bias on the tube 93 of the high gain amplifier 29 is controlled by the synchronizing impulses.

Assume, for example, that the amplifier 29 starts to drift in a direction such that the plate current of the last tube 101 increases. This causes a decrease in the positive potential at the anode 111 whereby the control grid 127 of the balancer tube 123 becomes more negative. This increase in negative bias is indicated by the dotted line 209. The picture signals and the synchronizing signals are likewise shifted as indicated by their dotted line positions.

The greater the shift of the synchronizing impulses in a negative direction, the less the value of the plate current pulses appearing in the output circuit of the balancer tube 123. This decrease in plate current pulses is indicated by the dotted line positions of the plate current rectangles shown at 205a. The smaller values of plate current pulses are integrated by the condenser 31 to produce a steady flow of biasing current having a decreased value as indicated by the dotted line 211.

It follows that an increase in current in the output circuit of the direct-current amplifier 29 causes a decrease in the negative bias applied to the input circuit thereof, and, since this decrease in negative bias causes a decrease in plate current in the amplifier output circuit, a balance is effected. In other words, before the output current of the amplifier 29 can either increase or decrease any appreciable amount, the bias on the first tube 91 of the amplifier is changed to counteract the change in output current.

The completeness of balance or the percentage of drifting which is balanced out is proportional to the gain around the closed loop from the balancer control grid 127 through the amplifier 29 and back to the balancer control grid 127. For example, considering the circuit shown in Figure 4, if the gain around the loop is 10,000 (considering included the effect of having the balancer tube 123 operative only a small percentage of the time), and the plate voltage of the amplifier tube 91 varies or drifts one volt, a change in voltage on the grid 105 of the second amplifier tube 101 of one ten-thousandth volt would be enough to cancel out the one volt change completely. However, as this action cannot take place, the new equilibrium point is something less than one ten-thousandth volt different on the grid 105 of the second amplifier tube than it was before the one volt drift occurred. The balance action is then more than 99.99% complete.

The highest frequency of noise that may be balanced out is determined by the capacity of the condenser 31 and by the period of the synchronizing impulses. Noise of near or about the synchronizing frequency cannot be balanced out

because it may happen between successive synchronizing impulses. Nothing is gained, therefore, by decreasing the capacity of the condenser beyond a certain region because no more of the noise spectrum can be eliminated and, as the condenser gets smaller, a larger modulation of the picture background results. That is, if the capacity of the condenser 31 is too small, or if the resistance of the plate resistor in shunt thereto is too small, the value of the bias on the control grid 95 of the amplifier tube 91 will change appreciably between synchronizing impulses. The condenser 31 should have sufficient capacity to prevent any appreciable modulation of the picture background. On the other hand, it should not be so large that the balancer responds too slowly to changes in the condition of the amplifier, since when drifting occurs it should be corrected immediately.

From the above remarks it will be appreciated that the capacity of the condenser 31 and the resistance of the plate resistor 137 may have values varying within wide limits. As an example of suitable values, however, a condenser having a capacity of one microfarad and a resistor having a resistance of 100,000 ohms have been found satisfactory.

Referring to Figure 6, where parts similar to those in Figure 1 are indicated by like reference numerals, a circuit is shown in which the synchronizing impulses are not transmitted through the high gain direct-current amplifier 29. Instead, they are amplified to the necessary value in the synchronizing amplifier 43, and supplied in proper phase through a potentiometer 215 to the transmission line 1-3.

The synchronizing impulses are supplied to the input circuit of the balancing amplifier 33 through a conductor 217 for the purpose of controlling the balancing circuit in the manner described above.

An amplifier 219 comprising two electric discharge tubes connected in cascade is provided to prevent the synchronizing impulses which are supplied to the balancer amplifier 33 through the conductor 217 from being impressed upon the transmission line 1-3. It will be noted that this permits the application of balancing impulses and synchronizing impulses to the amplifier 33 and the line 1-3, respectively, having different amplitudes whereby the control of the system is more flexible. If desired, the blocking amplifier may consist of an odd number of tubes, but in that case the number of tubes in either the amplifier 29 or in the balancer circuit 33 must be changed in order to feed energy from the output of the amplifier 29 to its input in the proper phase to oppose changes in the output current.

From an inspection of Figure 6, it will be apparent that, if it is desired to transmit picture signals free from synchronizing impulses, the connection through the potentiometer 215 may be omitted. In this case the impulses which are supplied from the synchronizing amplifier 43 serve only to prevent drifting of the direct-current amplifier. This modification is of particular value where the amplifier is utilized for purposes other than the amplification of picture signals.

It will also be evident to those skilled in the art that various expedients may be employed for interrupting signal voltages periodically and supplying control impulses of the opposite polarity during the periods these signals are interrupted.

An example of such an expedient will now be described and although it, like the preceding embodiment of the invention, is described in connection with the transmission of pictures, it 5 should be understood that my improved direct-current amplifier is of general application.

A separate generator for the synchronizing or balancing impulses may be omitted by giving the picture a steady component of light of such value 10 that the variations due to the picture never modulate the light more than a certain percentage. A picture signal having this character is shown in Figure 7. It will be noted that the picture signal is always above the dotted line axis 221, while during the interval between line scanning the signal drops to a zero value. With respect to the dotted line axis 221, this zero 15 value of current corresponds to a current impulse having a polarity opposed to that of the signal current and, therefore, it may be utilized for synchronizing and for controlling the balancer circuit 33 in the manner previously described.

One form of apparatus for obtaining the type of 20 picture signal shown in Figure 7 is illustrated in Figures 8 and 9, where parts similar to those in Figure 1 are indicated by like reference numerals.

Referring to Figures 8 and 9, the steady component of light is supplied to the photoelectric 25 cell 19 by means of a half-silvered mirror 223 positioned between the scanning disc 7 and the film 15. A portion of the light passes through the half-silvered mirror 223, while another portion is reflected to a mirror 225 and, from the 30 mirror 225, to the photoelectric cell 19.

As shown in Fig. 10, the synchronizing holes 35 are preferably omitted from the scanning disc 7 when employing the half-silvered mirror 223 since they would have no function, the mask 40 227 being of the proper dimensions to provide a synchronizing interval during which no light passes through the scanning disc.

Although I have described the preferred embodiment of my invention in which the picture 45 signals and the synchronizing signals are of opposite polarity, it should be understood that they may be of the same polarity providing the synchronizing signals are given an amplitude considerably greater than the amplitude of the picture signals.

For example, referring to Fig. 5, if the picture 50 signals are given a positive polarity at the balancer tube 123 and an amplitude which is approximately one-half of the amplitude of the synchronizing signals, it will be apparent that only the synchronizing impulses will produce a flow of current in the plate circuit of the balancer tube. Signals of this character can be obtained by providing the proper number of amplifier 55 stages in the picture and synchronizing channels in accordance with well known practice.

From the foregoing description, it will be understood that various modifications may be made in my invention without departing from the spirit 60 and scope thereof, and I desire therefore that only such limitations shall be placed thereon as are necessitated by the prior art and are set forth in the appended claims.

I claim as my invention:

1. The method of operating a direct-current 65 amplifier for amplifying electrical energy which comprises impressing said energy upon the input circuit of said amplifier periodically whereby there are intervals during which said energy is not being impressed thereon, impressing a voltage impulse 70

upon said input circuit during each of said intervals which has a polarity opposed to the polarity of said electrical energy, amplifying said voltage impulse in said amplifier whereby the amplified impulse has a value depending upon the condition 5 of said amplifier, and controlling the condition of said amplifier in accordance with said amplified impulse.

2. The method of operating a direct-current 10 amplifier for amplifying signal voltages which comprises impressing said signal voltages upon the input circuit of said amplifier periodically, whereby there are intervals of no signal voltage, and applying biasing impulses to said amplifier during and only during said intervals for controlling a bias voltage in said amplifier.

3. The method of operating a direct-current 15 amplifier which comprises impressing thereon periodically signal energy to be amplified whereby there are blank periods during which said signal 20 energy is not being impressed upon said amplifier, and applying biasing energy to said amplifier during said blank periods, said energy having a value dependent upon the condition of said amplifier during said blank periods.

4. The method of operating an amplifier for 25 amplifying electrical signals which comprises impressing said signals upon the input circuit of said amplifier periodically, whereby there are intervals during which said signals are not impressed upon said input circuit, impressing a control voltage upon said amplifier during each of said intervals to produce an amplified energy impulse, storing up each of said amplified impulses in accordance with the condition of said 30 amplifier during the preceding signal period, and controlling the condition of said amplifier during the succeeding signal period in accordance with said stored energy.

5. In a picture transmitting system including 40 a direct current amplifier, the method of transmitting pictures which comprises transmitting picture signals corresponding to scanning lines, transmitting synchronizing signals between scanning lines, impressing said signals upon said 45 direct-current amplifier, amplifying said synchronizing signals in accordance with the direct-current component appearing in the output of said amplifier, and applying a control voltage to said amplifier having a value which depends upon 50 said amplified synchronizing signals and having the proper polarity to oppose any change in said direct-current component.

6. In combination, a direct-current amplifier having an input circuit and an output circuit, a 55 second direct-current amplifier means for so coupling said output circuit to said input circuit through said second amplifier that a degenerative loop circuit is formed, means for impressing signal voltages at one time and control voltages at 60 a different time upon said input circuit, and means for permitting only said control voltages to pass through said loop circuit.

7. In combination, a direct-current amplifier having an input circuit and an output circuit, a 65 second direct-current amplifier, means for so coupling said output circuit to said input circuit through said second amplifier that a degenerative loop circuit is formed, means for impressing signal voltages and control voltages 70 alternately upon said input circuit, and means for permitting only said control voltages to pass through said loop circuit.

8. In combination, a direct-current amplifier having an input circuit and an output circuit, a 75

second direct-current amplifier, means for so coupling said output circuit to said input circuit through said second amplifier that a degenerative loop circuit is formed, means for impressing signal voltages and control voltages alternately upon said input circuit, means for preventing the circulation of said signal voltages in said loop circuit, and means for controlling a bias voltage in said amplifier in accordance with said control voltages.

9. Apparatus according to claim 8 characterized in that said coupling means includes an electric discharge tube having a bias voltage which varies in accordance with the direct-current component of the output of said amplifier.

10. A direct-current amplifier having an input circuit and an output circuit, feed-back means for feeding energy from said output circuit to said input circuit in the proper phase to oppose any change in the output of said amplifier, means for impressing signals upon said input circuit periodically, and means for making said feed-back circuit inactive during the periods said signals are being impressed upon said input circuit and for making it active during the intervals between said signal periods.

11. Apparatus for amplifying signal voltages, said apparatus comprising a direct-current amplifier having an input circuit and an output circuit, a feed-back circuit coupling said output circuit to said input circuit, said feed-back circuit including an electric discharge tube biased to the region of cut-off and being connected to oppose any change in current in said output circuit, means for impressing said signal voltages periodically upon said input circuit whereby there are intervals of no signal, means for impressing voltage pulses upon said input circuit during said intervals, said pulses having the proper polarity to cause a positive voltage pulse upon the input electrodes of said electric discharge tube.

12. Electrical apparatus comprising an amplifier having an input circuit, means for impressing signal voltages upon said input circuit period-

ically whereby there are signal periods separated by intervals of no signal, means for applying a control voltage to said amplifier during each of said intervals whereby each control voltage is amplified to a value corresponding to the condition of the amplifier during the interval the said control voltage is applied, means for charging a condenser in accordance with the value of said amplified control voltage, and means for controlling said amplifier in accordance with the charge on said condenser.

13. A direct-current amplifier having an input circuit and an output circuit, means for so coupling said output circuit and said input circuit that a degenerative loop circuit is formed, said coupling means including an electric discharge tube biased beyond cut-off, means for producing signal voltages and control voltages of opposite polarity and for impressing them alternately upon said input circuit, said loop circuit being so designed that said control voltages are of positive polarity when impressed upon said electric discharge tube whereby they are passed through said loop circuit, means responsive to a change in the output of said amplifier for changing the bias of said electric discharge tube whereby pulses of control current appear in the output circuit of said tube having values depending upon said change in bias, and means including a condenser shunted by a resistance unit for applying a controlling voltage to said direct-current amplifier, said coupling means being connected to charge said condenser in accordance with said pulses of control current.

14. The method of maintaining the amplification factor of a direct-current amplifier substantially constant which comprises supplying signals to the amplifier periodically whereby there are intervals during which said signals are not supplied thereto, supplying control signals to the amplifier during said intervals, deriving from the amplified control signals a unidirectional potential and utilizing said potential for controlling the gain in the amplifier.
